FASTENING PULLING MACHINE

Lawrence E. Steimen, Beverly, Mass., assignor to
United Shoe Machinery Corporation, Flemington, N. J., a corporation of New Jersey

Application July 10, 1945, Serial No. 604,217

6 Claims. (Cl. 12—16)

1

This invention relates to improvements in fastening pulling machines, and is herein illustrated as embodied in a machine for pulling tacks from shoes.

In the manufacture of shoes in the removal of temporary fastenings inserted in the shoes, such as lasting tacks or staples, or insole tacks, it has heretofore been customary to make use of a pick or claw tool, which is moved in an orbital path to pull the fastening from the shoe. Commonly, in order to make it possible for the operator to observe the action of the tool at the operating point, the path of movement of the tool in pulling a fastening is in a forward direction, that is, in the general direction of the operator. In the past, various mechanisms have been employed to prevent the fastenings from being thrown in such a way as to involve likelihood of injury to the operator. Some of these have been generally satisfactory, but those which are highly efficient in preventing fastenings from striking the operator tend to obscure the view of the operating point, thus making it difficult to present the shoe in proper operative position relatively to the fastening pulling tool.

In view of the foregoing, it is an object of the present invention to provide an improved fastening pulling machine, which, while providing an unobstructed view of the operating point, will at the same time be so constructed and arranged as to prevent fastenings from being thrown toward the operator.

To this end and as illustrated, I have provided in a machine of the type referred to a fastening pulling tool movable in an orbital path, there being a work rest extending along a portion of the path, and a guard member extending across the path in position to arrest forward movement of fastenings pulled from the work by the tool.

Preferably and as shown, the guard member comprises a spring pivotally mounted upon portions of a work rest extending upon opposite sides of the path of the tool and is constructed and arranged to span the space between the portions. The free end of the spring is spaced from that portion of the path along which initial engagement of the tool with a fastening takes place, so that the operator can readily visually locate the fastening to be pulled relatively to the tool. There is provided a cam associated with the tool for moving the spring outwardly during the pulling operation, so that as the fastening is pulled the spring is positioned between the fastening and the operator, and upon rearward movement of the

2

cam the spring operates to throw the fastenings rearwardly.

These and other features of the invention are disclosed in the following specification and in the accompanying drawings, and are set forth in the claims.

In the drawings,

Fig. 1 is a side view, partly in section, of a portion of a fastening pulling machine embodying one form of my invention;

Fig. 2 is a front end view of the portion of the machine shown in Fig. 1; and

Figs. 3 and 4 are side views of the machine of Fig. 1 with the parts in different positions to illustrate the cycle of operation of the machine.

The invention is illustrated as embodied in a fastening pulling machine of the type disclosed in United States Letters Patent No. 2,266,124, granted December 16, 1941, upon application filed 10 in the name of Harry Lyon, to which reference may be had for a disclosure of portions of the machine not herein illustrated in detail.

As shown in Fig. 1, the machine comprises a tack pulling tool 10 mounted for movement in 15 an oscillatory path along a work rest 12 for pulling insole tacks 14 from a shoe 16.

The tack pulling tool is in the form of a chisel and is positioned in a tool holder 18 carried at the lower end of a tack puller bar 20 arranged to oscillate on a pin 24 mounted on a pivot 26 on a portion 28 of the frame of the machine. The tack puller bar is moved about the pivot 26 and along the pin 24 by mechanism (not shown) for producing an orbital movement 30 of the tack puller tool along a path indicated by the dashed line 30. For a more complete description of the construction and operation of the machine thus far described, reference may be had to the aforementioned United States Letters Patent.

The pulling mechanism is supported by a column 32, which has a lateral projecting bracket 34 to which the work rest 12 is secured. To this end, the work rest has a rearwardly extending portion 36 resting in a recess 38 in the bracket 34 and secured in position therein by means of a bolt 40. The forward part of the work rest is forked, having two arms 42 extending substantially in a horizontal plane. The outer ends of the arms are curved upwardly, as shown at 44, and are spaced relatively to each other by an increasing distance in an upward direction, forming substantially a V-shaped opening. The work rest is positioned so that the arms 42 and the upwardly extending portions 44 are located upon

opposite sides of the plane of the path of movement of the pulling tool 10. By adjusting the work rest in or out relatively to the tool, the work rest can be located in such position that the lowermost portion of the path of the tool extends slightly beyond the under surfaces of the arms adjacent to the horizontal portions thereof, thus to permit the tool in its movement to project beyond the arms for a short distance along the path, as is necessary in order that the tool may penetrate into the insole of the work in pulling a fastening therefrom.

Provision is made for arresting forward movement of fastenings pulled from the work, said means comprising a leaf spring 46 secured by bolts 48 to a crosspiece 50, which, in turn, is secured to portions 44 by screws 52. The spring is straight for a short distance, and then curves inwardly, as shown at 54, and then outwardly at its lower end, as shown at 56. The lower end portion of the spring in its normal position, as shown in Fig. 1, is somewhat above the lower portion of the path of movement of the tool, and is substantially in line with the portion of the path of the tool during its movement in pulling a fastening. Inward movement of the spring is limited by a cam 58 formed on the outer end of the work holder 18. This construction is such that, as the tool is moved in its orbital path, the cam 58 will engage the curved portion 54 of the spring and gradually force it outwardly and downwardly across the path of the tool, as shown in Figs. 1, 3 and 4. For example, as shown in Fig. 1, the tool is in its fastening pulling position, that is, along the operative portion of its path with the spring somewhat above the tool. As shown in Fig. 3, the tool has been moved outwardly and upwardly to effect removal of a tack and, in the meantime, the cam 58 has forced the spring outwardly beyond the tool and the pulled tack, thus preventing movement of the tack in a direction toward the operator. Fig. 4 shows the parts in position with the tool moving inwardly and downwardly in the latter half of its cycle, and the spring, which has just been released from the cam, is in engagement with the end of the tool, and is in the act of forcing the tack in a rearward direction.

In order to dispose of the pulled fastenings, the work rest is provided with a floor 60 extending between the two arms 42 from a point adjacent to but rearwardly of the operating part of the tool path and extending rearwardly close to the shank portion 36 of the work rest. A chute 62 is secured to the underside of the bracket 34 by means of a bolt 64. The chute has an upwardly extending lip 66 positioned below the inner edge of the floor 60, arranged to receive fastenings which drop off the floor. To the inner end of the chute is connected a hose 68 which serves to direct fastenings, which drop into the chute, into a receptacle 70.

In order to arrest movement of pulled fastenings in lateral directions, the work rest has secured thereto two screen plates 72 extending between the horizontal arms 42 and the upwardly extending arms 44 on each side of the tool holder.

In the operation of the machine, a shoe, such as shoe 16, with insole tacks to be pulled is presented to the work rest, the shoe moved in such direction as to locate the tack to be pulled in line with the path of movement of the tool 10. By movement of the tool in its orbital path, the tack will be removed from the insole and moved forwardly and upwardly, during which time the

spring 46 will engage the tack, arresting its forward movement, and upon rearward movement of the tool the spring will throw the tack rearwardly away from the operating point of the machine. The guard thus is operative not only to prevent the forward movement of the fastenings out of the machine, but operates to direct them toward the chute 62, where they can readily be removed from the machine.

Upon inspection of Fig. 2, it will be noticed that the guard or spring 46 extends downwardly, spanning the space between the arms 44 of the work rest, but that the guard does not cover the tool at its initial operating point, that is, at the point where the pulling operation commences. Consequently, the operator is at all times able to see the tool at its operating point, which facilitates the presentation of the fastening in proper position to be pulled.

Having described my invention, what I claim as new and desire to secure by Letters Patent of the United States is:

1. A fastening pulling machine comprising a pulling tool mounted for movement in an orbital path, a work rest adjacent to the path of the tool and having portions extending upon opposite sides of the path, supporting members extending upwardly from the work rest, and a leaf spring pivotally mounted at the upper ends of the supporting members and constructed and arranged substantially to span the space between the members for arresting forward movement of fastenings pulled from the work by the tool.

2. A fastening pulling machine comprising a pulling tool mounted for movement in an orbital path, a work rest adjacent to the path of the tool and having portions extending upon opposite sides of the path, spaced supporting members extending upwardly from the work rest, and a guard member pivotally mounted upon the supporting members and extending across a portion of the path of the tool for arresting forward movement of fastenings pulled from the work by the tool.

3. A fastening pulling machine comprising a frame, a pulling tool mounted in the frame for movement in an orbital path, a work rest carried by the frame and located adjacent to the path of the tool, said work rest having upwardly extending portions positioned upon opposite sides of the path of the tool, and a guard member pivotally mounted upon said portions and extending across a portion of the path of the tool for arresting forward movement of fastenings pulled from the work by the tool.

4. A fastening pulling machine comprising a pulling tool mounted for movement in an orbital path, a bifurcated work rest extending on opposite sides of the path of the tool and adjacent thereto, a leaf spring carried by the work rest and extending across the path of the tool, and means associated with the tool for moving the spring outwardly away from the path of the tool during initial movement of the tool in pulling a fastening.

5. A fastening pulling machine having a pulling tool mounted for movement in an orbital path, a work rest adjacent to the path of the tool and having portions extending upon opposite sides of the path and forwardly and upwardly beyond the path, a leaf spring pivotally mounted upon said portions and constructed and arranged to span the space between said portions forwardly of the path of the tool, the spring having an inwardly extending central portion and an outwardly

extending lower end portion located adjacent to the portion of the path in which the tool moves upwardly in pulling a fastening from work presented to the work rest, and a cam associated with the tool for engaging the inwardly extending portion of the spring during movement of the tool for controlling the position of the lower end portion of the spring relatively to a fastening being pulled.

6. A fastening pulling machine comprising a

pulling tool mounted for movement in an orbital path, guard members positioned upon opposite sides of the path of the tool, a leaf spring pivotally mounted upon the guard members and extending across the space between the members beyond the tool, and a cam operable in timed relation to the tool for moving the spring outwardly during movement of the tool in pulling a fastening.

LAWRENCE E. STEIMEN.
